UNITED STATES PATENT OFFICE.

JAMES RUDOLPH HOLY, OF LA CROSSE, WISCONSIN, ASSIGNOR OF ONE-HALF TO
SEGELEKE & KOHLHAUS MFG. CO., OF LA CROSSE, WISCONSIN.

GLAZIER'S-POINT SETTER.

1,342,110.

Specification of Letters Patent.

Patented June 1, 1920.

Application filed December 20, 1919. Serial No. 346,281.

To all whom it may concern:

Be it known that I, JAMES RUDOLPH HOLY, a citizen of the Republic of Czechoslovakia, residing at La Crosse, in the county of La 5 Crosse and State of Wisconsin, have invented certain new and useful Improvements in Glaziers'-Point Setters, of which the following is a specification.

My invention relates to glaziers' point 10 setters, and particularly to that shown in Patent 252,379, January 17, 1882, to G. W. Hubbard.

The object of the invention is to improve the Hubbard construction by forming 15 the rear portion of the driver or striker in a higher plane than its forward portion so that its elevated rear portion may overlie a sash stile or rail in driving points in a narrow transom or sash and so permit the implement to rest flat upon the 20 pane of glass.

A further object is to provide the rear 25 end of the implement with a vertically movable block adapted in its lowered position to rest on the pane of glass and assist in supporting the implement flat upon the pane of glass and not at an angle thereto and adapted when moved upwardly to allow the rear end of the implement to overlie 30 a stile and so permit said implement to rest flat upon the pane.

By the aforesaid construction the implement will always lie flat upon the pane of glass and not be raised at an angle thereto 35 as would be the case with a striker or driver formed without the offset between its ends as in my improved construction.

These objects I accomplish by the construction shown in the accompanying drawing, in which:

Figure 1 is a sectional side elevation of my improved point setter in use on a small pane with the block swung up.

Fig. 2 is a side elevation with the block 45 swung down.

Fig. 3 is a fragmentary rear end view of the implement.

Fig. 4 is a plan of the striker or driver plate.

The frame 1 of the implement has at its 50 front vertical wall a magazine 2 for the points to be driven and a follower 3 rests on the upper end of the pile of points and forces them down to the outlet 4 in a flat 55 horizontal plate 5 secured to the lower end

of the magazine and projecting at its side edges therebeyond. A striker or driver 6 with inturned edges 7 slides on the plate 5 and has secured to its lower side a striker plate 8 having a notch 9 in its front edge 60 shaped to engage the point to be set or driven and of about the thickness of said point. The upper side of the striker or driver 6 has a latch 10 pivoted between its ends, provided at its rear end with an 65 adjusting screw 11 and provided under its opposite end with a spring 12. This latch 10 is engaged by the lower end of the downwardly extending member 13 of a bell crank 70 lever 14 pivoted at its angle to the upper forward end of the implement. The hand engaged member 15 of the bell crank lever extends under the top bar of the implement frame so as to be grasped by the operator in the operation of driving or setting 75 the points.

The above described construction is that of the well known and generally used Hubbard implement above described.

In my present construction the striker 80 or driver has a vertical offset 19 so that its rear end 20 carrying the spring 21 is raised into a higher plane than the forward or working end. The rear end of the implement frame terminates in a hinged 85 bearing block 22 instead of the block shown in the Hubbard patent and both sections 22, 23 of this block 22 are perforated for the rear end 20 of the striker or driver, as at 24, 25. When the swinging section 23 90 is swung down it will be held in position by a pivoted button 27 or the like, and when it is swung up it will be held by a hook 28 and catch or pin 29. The section 22 is secured to the apertured rear depending end of the frame by screws or bolts, as shown.

As shown in Fig. 1, where the sash stiles are spaced apart about the length of the implement, the swinging section 23 is moved 100 upwardly and latched to the other section 22 so that the implement as a whole will rest flat upon the glass and sash stile and so avoid tilting of the implement and the driving of the point at an angle. So also in Fig. 105 2, where a very narrow pane or light is being secured, the implement will be prevented from being tilted or inclined vertically by reason of the offset in striker or driver and the downward swinging of the block 23.

It will be understood that the implement must lie perfectly flat upon the pane to properly drive the points without danger of breaking the glass, for I have found excessive breaking of the glass where the implement is on a vertical inclination; moreover this inclination of the implement would allow of two points dropping from the magazine. This is all avoided by my construction.

Furthermore, I provide the implement with lateral wings 30 to prevent it from tipping laterally on the pane. These wings 30 project from the side edges of the driving plate 8 in the horizontal plane thereof and greatly steady the implement.

I have been able to use my improved implement on lights or panes as small as four inches square, which was impossible with the old form. This implement will always lie flat on the glass even with these small lights.

What I claim is:

1. A glazier's point setter of the character described provided with a driver or striker having its rear portion in a plane sufficiently higher than its striking end to overlie and clear a stile and permit the striking end to lie flat on a pane of glass.
2. A glazier's point setter of the character described provided with a driver or striker sufficiently offset vertically between its ends,

whereby its rear higher portion will overlie and clear a stile and permit the striking end to lie flat on the pane of glass.

3. A glazier's point setter of the character described provided with a driver or striker sufficiently offset vertically between its ends to permit its rear portion to overlie and clear a stile and its striking end to rest flat on a pane of glass and provided also with a vertically movable block or support at the rear end to support the implement at all times in a horizontal position.

4. A glazier's point setter of the character described provided with a driver or striker sufficiently offset vertically between its ends to permit its rear portion to overlie and clear a stile and its striking end to rest flat on a pane of glass and provided also with a sectional hinged block or support at the rear end to support the implement at all times in a horizontal position.

5. A glazier's point setter of the character described provided with a driver or striker sufficiently offset vertically between its ends to permit its rear portion to overlie and clear a stile and its striking end to rest flat on a pane of glass and having lateral wings or projections at its working or driving portion to support the implement from lateral inclination.

In testimony whereof I affix my signature.

JAMES RUDOLPH HOLY.
